UNITED STATES PATENT OFFICE.

CLARENCE WILLIAM AIRD, OF BRANTFORD, ONTARIO, CANADA.

OVEN FOR BAKING AND INDUSTRIAL PURPOSES.

1,320,821.

Specification of Letters Patent.

Patented Nov. 4, 1919.

Application filed April 14, 1919. Serial No. 289,941.

To all whom it may concern:

Be it known that I, CLARENCE W. AIRD, of the city of Brantford, in the county of Brant and Province of Ontario, Dominion of Canada, have invented certain new and useful Improvements in Ovens for Baking and Industrial Purposes; and I hereby declare the following to be a full, clear, and exact description of the same.

10 This invention relates particularly to oven walls, which consist of peculiarly constructed sections or panels, insulated against heat loss and maintained in their assembled relation by interlocking, self-sealing joints; 15 the objects of the invention being:—

(a) to provide for expansion strains, resulting from relatively high temperatures and pressures within the oven during its use; (b) to eliminate heat loss, by preventing 20 leakage, convection, and conduction. (c) to simplify the construction, assembly, transportation, and erection of the walls; and (d) to provide a mechanically strong 25 structure without detracting from its insulating properties;

These objects being attained by the construction hereinafter set forth and particularly pointed out in the claims.

30 For an understanding of the invention, reference is to be had to the following description, and to the accompanying drawings in which;

Figure 1, is a fragmentary view of an 35 oven, constructed of sections or panels.

Fig. 2, is a perspective view of one of the sections or panels, shown in Fig. 1.

Fig. 3, is a perspective view of part of the casing of the section or panel shown in 40 Fig. 2.

Fig. 4, is a perspective view of the channel shown in Fig. 2.

Fig. 5, is a perspective view of the remainder of the casing of the section or panel 45 shown in Fig. 2.

Fig. 6, is a longitudinal section on the line a—a, Fig. 2.

Fig. 7, is a cross sectional view on the line b—b, Fig. 2, and

50 Fig. 8, is a horizontal section through the corner of the oven, shown in Fig. 1.

Like characters of reference refer to like parts throughout the specification and drawings.

55 Fig. 1 shows a side wall, consisting of four sections or panels a, and a portion of the

front wall, comprising a section or panel b, these being sufficient to explain the construction, assembly and erection of the walls of an oven, such for instance of the type 60 shown in Letters Patent No. 626,773, dated June 13, 1899.

Each of the panels shown in Fig. 1, extends the full height of the oven, and is composed of a hollow casing filled with heat 65 insulating material c, and preferably constructed as hereinafter described.

Along one of the vertical edges d, of the section or panel, is a channel of relatively considerable depth, and of an interior width, 70 corresponding to the thickness of the other vertical edge d', of the same section or panel.

For convenience of assembly the sections or panels are standardized, so far as height and thickness are concerned, and being of 75 corresponding dimensions, in this respect, the channel of one section or panel will receive and tightly embrace the opposite edge d' of the next adjacent section or panel, so that during the erection of the walls, the 80 edge d' of each section or panel may be pressed into the channeled edge d, of the next adjacent section or panel, until all of the sections or panels of the wall have been assembled; but the width of the panels may 85 vary as that dimension will depend to a large extent on the length of the oven.

The parallel sides d'', d³, of the channels, are preferably flexible and of such mechanical strength as to exert sufficient pressure on the sections or panels, to not only maintain the assembly without the use of rivets, bolts or other fastening devices, but also form a substantially gas or air tight joint, and thereby prevent heat leakage from the interior of the oven. The sections or panels have, by this means of assembly, a limited 90 freedom of movement when expanding and contracting during the variations of temperature and pressure within the oven, which 95 relieves the walls of the strains otherwise resulting therefrom.

A simple method of constructing each section or panel is to make the channel d from sheet metal, of suitable dimensions, and cut and bend it to form the channel bottom or side d⁴, spaced sides d'', d³ and end flanges d, the flanges d⁵ being bent at appropriate angles to the bottom or side d⁴ to project beyond it in a direction opposite to the spaced 100 sides d'', d³.

The casing of the section or panel consists

of two parts; which may for convenience, be termed the "pan" and the "cover."

The pan, as shown in Fig. 3, is made from sheet metal cut and shaped to form a relatively wide side e , a narrow side e' lengthwise of the side e and at right angles thereto, and two transverse sides e'' , e^3 , at the extremities of the side e .

In cutting the blank, from which the pan is made, sufficient metal is provided in the case of the side e , to permit of its extremities being bent inward, to form two flanges f , f' , which abut against the sides e'' , e^3 , to which they are secured preferably by rivets f'' , and sufficient metal is also provided along the free edge of the side e' to form a fold g , for the purpose hereinafter described.

As shown in Fig. 3, the side e is extended beyond the sides e'' , e^3 , and is formed with a fold g . When the pan and the channel are assembled, the side d'' of the channel is contained in the fold g and the bottom side d^4 of the channel and the sides e , e' , e'' , e^3 , then constitute five sides of the casing.

In assembling the above described parts, the side d'' of the channel is inserted in the fold g , which is pressed to tightly embrace it and hold it securely in its assembled relation without the use of other fastening means and the flanges d^5 , are positioned to abut against the inner surface of the sides e'' , e^3 , to which they are secured, preferably by rivets, as shown at g'' .

The channel bottom or side d^4 , and the sides e , e' , e'' , e^3 , are all of the same height, so that the cover h will lie evenly thereon.

To provide a simple means of securing the cover to the pan and channel, the sides e'' , e^3 , are provided with outturned flanges i , i' , at right angles to the sides e'' , e^3 , respectively, and the cover h is formed with folds h' , h'' , h^3 , h^4 , along its four edges, into which enter the side d^3 of the channel, the fold g' along the top of the side e' and the flanges i , i' , at the top of the sides e'' , e^3 . When the cover and the pan are assembled, the folds h' , h'' , h^3 , h^4 , are tightly pressed against the parts contained within them, and the cover is then firmly secured to the pan without the use of bolts, rivets, or the like.

To prevent heat loss by convection or conduction, sheets of insulating material, j , j' are interposed between the flanges i , i' respectively, and the cover, this insulation overlapping the edges of the sides e'' , e^3 , sufficient for that purpose.

When the cover is provided with a base, the flange i is out-turned as shown in Fig. 3, but when the base is not used the flange may be inturned or omitted.

For the corner or angle section or panel, the channel side d''' and fold g are omitted and the channel side d^3 is bent around the

adjacent edge of the panel b , as shown in Fig. 8.

In this case the corner panel or section a is provided with an angle iron, or angle brackets h , riveted to the section, and bolts 70 are passed through the bent side d''' , the section or panel b , and angle iron or brackets h to secure the corner panels or sections together.

The top of the oven may consist of panels 75 or sections similar to those of the side walls, and may be supported on the top of the side panels or sections where they are held against displacement by the flanges i' .

This construction permits of limited expansion, and contraction longitudinally, vertically and laterally.

When the sections or panels are of relatively considerable width, a brace or set of braces m , may be employed to maintain the 85 spaced relations of the side e and cover h , the brace or braces extending preferably the full height of the section or panel.

In Fig. 3, the brace is shown to be substantially V shaped in cross section, with a 90 sheet of insulation m' , between the flanges m'' and the side e , the brace being preferably secured in position by rivets or bolts m^3 , passing through the flanges, insulation and said side.

Insulating material, c , either of a fibrous, granular or cellular character may be employed within the section or panel to prevent heat loss.

While I have described in detail one specific means of carrying the invention into practice, I wish it to be understood that various changes in the structural details may be made within the scope of the appended claims, without departing from the principle of the invention.

Having thus fully described my invention, what I claim as new and desire to secure by Letters Patent is:

1. An oven for baking and industrial purposes comprising a wall composed of a set of sections or panels, each of which has a channel of U-shape along one edge, adapted to receive the opposite edge of the next adjacent section or panel, and form with it 105 an interlocking self-sealing joint, said channel being of a unitary structure with the body of the section or panel.

2. An oven for baking and industrial purposes comprising a wall composed of a set 110 of sections or panels each of which has a channel of U-shape along one edge, formed with flexible parallel sides, adapted to receive between them the opposite edge of the next adjacent section or panel and form 125 with it an interlocking self-sealing joint which maintains the assembly of the sections or panels without the use of fastening means and provides for the expansion strains resulting from changes of temperature and 130

pressure within the oven, said channel being of a unitary structure with the body of the section or panel.

3. An oven for baking and industrial purposes comprising a wall composed of a set of sections or panels, each of which has a channel of U-shape along one edge, adapted to receive the opposite edge of the next adjacent section or panel, and form with it 10 an interlocking self-sealing joint and means within the channel for insulating the joint, said channel being of a unitary structure with the body of the section or panel.

4. An oven for baking and industrial purposes, having a wall composed of sections or panels, each comprising a hollow casing, internally braced and filled with insulating material, and provided exteriorly along one edge, with a channel, to receive the opposite 15 edge of the next adjacent section or panel and form with it an interlocking, self-sealing joint, which maintains the assembly of the sections or panels without the use of fastening means and provides for the expansion strains resulting from changes of temperature and pressure within the oven.

5. An oven for baking and industrial purposes, having a wall composed of sections or panels each comprising a hollow casing 30 consisting of a pan, made from sheet metal cut and shaped to form a relatively wide side, a narrow side, lengthwise of one edge of the relatively wide side and at a suitable angle thereto, a fold along the free edge of the 35 narrow side, a fold along the edge of the relatively wide side, opposite to that of the narrow side, transverse sides at the extremities of the relatively wide side, and of corresponding depth to the narrow side, flanges at the ends of the narrow side abutting 40 against the inner surfaces of the transverse sides and riveted thereto, a channel consisting of a side having flanges abutting against the inner surfaces of the transverse 45 sides and riveted thereto, and two parallel sides to receive between them the opposite edge of the adjacent section or panel, one of said parallel sides being contained within the fold of the relatively wide side, and a cover having folded edges to receive therein the other parallel side and the fold of the 50 narrow side, by which the pan and cover are secured together.

6. An oven for baking and industrial purposes, having a wall composed of sections or panels each comprising a hollow casing 55 consisting of a pan made from sheet metal cut and shaped to form a relatively wide side, a narrow side lengthwise of the one edge of the relatively wide side and at a suitable angle thereto, a fold along the free edge of the narrow side, a fold along the edge of the relatively wide side, and of corresponding depth to the narrow side, flanges 60 at the ends of the narrow side abutting

against the inner surfaces of the transverse sides and riveted thereto, a channel consisting of a side having flanges abutting against the inner surfaces of the transverse sides and riveted thereto, and two parallel sides to 70 receive between them the opposite edge of the adjacent section or panel, one of said parallel sides being contained within the fold of the relatively wide side, and a cover having folded edges to receive therein the 75 other parallel side and the fold of the narrow side, flanges for the transverse sides, and folded edges for the cover to receive said flanges.

7. An oven for baking and industrial purposes, having a wall composed of sections or panels each comprising a hollow casing consisting of a pan, made from sheet metal cut and shaped to form a relatively wide side, a narrow side, lengthwise of one edge 80 of the relatively wide side and at a suitable angle thereto, a fold along the free edge of the narrow side, a fold along the edge of the relatively wide side, opposite to that of the narrow side, transverse sides at the 85 extremities of the relatively wide side, and of corresponding depth to the narrow side, flanges at the ends of the narrow side abutting against the inner surfaces of the transverse sides and riveted thereto, a channel 90 consisting of a side having flanges abutting against the inner surfaces of the transverse sides and riveted thereto, and two parallel sides to receive between them the opposite edge of the adjacent section or panel, one of 95 said parallel sides being contained within the fold of the relatively wide side, and a cover having folded edges to receive therein the other parallel side and the fold of the narrow side, and insulation within the casing and between the cover, and said transverse and channel sides.

8. An oven for baking and industrial purposes, having a wall composed of sections or panels, each comprising a hollow casing 100 consisting of a pan made from sheet metal cut and shaped to form a relatively wide side, a narrow side lengthwise of one edge of the relatively wide side, and at a suitable angle thereto, transverse sides at the 105 extremities of the relatively wide side, and of corresponding depth to the narrow side, a channel side for the pan, a cover secured to the pan and channel side, and insulation within the casing.

9. An oven for baking and industrial purposes comprising a wall composed of a set of sections or panels, each of which has a channel of U-shape along one edge, adapted to receive the opposite edge of the next adjacent section or panel, and form with it an interlocking self-sealing joint, said channel being of a unitary structure with the body of the section or panel, and means insulating the channel therefrom.

10. An oven for baking and industrial purposes comprising a wall composed of a set of sections or panels each of which has a channel of U-shape along one edge, formed 5 with flexible parallel sides, adapted to receive between them the opposite edge of the next adjacent section or panel and form with it an interlocking self-sealing joint which maintains the assembly of the sections or panels without the use of fastening means and provides for the expansion strains resulting from changes of temperature and pressure within the oven, said channel being of a unitary structure with the 15 body of the section or panel, and means insulating the channel therefrom.

11. An oven for baking and industrial purposes comprising a wall composed of a set of sections or panels, each of which has a channel of U-shape along one edge, adapted 20 to receive the opposite edge of the next adjacent section or panel, and form with it an interlocking self-sealing joint and means within the channel for insulating the joint, said channel being of a unitary structure 25 with the body of the section or panel, and means insulating the channel therefrom.

Toronto, March 13th, 1919.
